BIB WITH POCKET

Harold J. Ralph, San Mateo, Calif.
(81 College Ave., Los Gatos, Calif.)
Filed Mar. 3, 1959, Ser. No. 796,809
4 Claims. (Cl. 2—49)

This invention relates to bibs having a pocket horizontally transversely across the lower portion thereof, and more particularly to such bibs in which a horizontally disposed pocket may be selectively held open or closed by pliable relatively spaced form-retaining integral strips each of which being bendable upon itself at an acutely angled arc to provide a pair of vertically disposed legs in substantially overlying layers, each leg being enclosed and bendable in an elongated strip tube in the bib pocket portion of the bib.

An object of the invention is to provide a moisture-impervious washable bib conveniently flexibly foldable in any direction, and having a bib pocket at a lower end which may be selectively opened and closed and maintained at such selective open or closed position.

A more particular description of the invention is set forth in this specification and illustrated in the accompanying drawing, in which:

FIG. 1 is a front elevational view of one form of the invention, partly broken away.

FIG. 2 is a fragmentary enlarged vertical section transversely on line 2—2 of FIG. 1.

FIG. 3 is a fragmentary enlarged horizontal section on line 3—3 of FIG. 1.

FIG. 4 is an enlarged view of a portion of FIG. 1.

FIG. 5 is a vertically sectioned fragmentary perspective view of a modified form of the invention, enlarged in relation to FIG. 1.

FIG. 6 is a section on line 6—6 of FIG. 5.

FIG. 7 is a perspective view of bendable strip member shown in both exemplified forms of the invention.

Referring to the drawing in which like reference characters indicate corresponding parts in the several views, and referring firstly to FIGS. 1 to 4 and 7, the reference character 10 indicates a bib body generally comprising a sheet of flexible material preferably impervious to penetration by moisture, and suitably formed of a suitable flexible sheet plastic, since such material may have its parts conveniently connected by either stitching or dielectric sealing, as is well known.

The bib comprises an upper breast portion 11 of such flexible sheet material, and may have at its upper edge portion an arcuately cut-out or opening 12 for encircling the neck of the wearer, as well as the usual tie strings 13, and may, if desired, be provided with shoulder wings 12a for covering the shoulders of the wearer, though these shoulder wings are elective and are not essential to the effective parts of the invention.

At one face of the lower portion of the breast portion 11 there is an elongated transverse horizontal pocket 15 which, in FIGS. 1 to 4, is an integral continuation of the single sheet of flexible body material of the breast portion, which at said lower portion may be folded or retroverted upwardly upon itself at an angle as at 15a to overlie the lower part of the breast portion, and preferably having its upfolded free terminal longitudinal horizontal edge thickened to resist wear and tearing by an integrally formed reinforcing rib 16, which is therefore also flexible, the opposite ends of the upfolded pocket being suitably securely closed, as by a closing plastic weld 17, thus providing the bib pocket with relatively opposed and relatively angularly connected planar front wall 14 and rear wall 19 integral with the

2

breast sheet portion, and the pocket being open at its upper horizontal longitudinal edge and closed at its opposite ends and bottom.

Spaced adjacently inwardly from each end of the horizontally transverse bib pocket, and spaced relatively to each other, are elongated flexible relatively flat continuous strip tubes 18, which are vertically or laterally transverse to the longitudinal horizontal bib pocket. In FIGS. 1 to 4, each of the strip tubes comprises an elongated flexible planar strip 18a preferably of material similar to the plastic bib material, said flexible strips overlying and being adhered by intimate plastic welding of the side edges and end edges thereof to the opposed walls of the bib pocket, preferably at the inner opposed faces of the pocket, whereby there is provided an elongated central portion of the said strips which is free of such welding and thereby provides the relatively flat continuous elongated strip tubes 18. The strip tubes 18 follow the contour of the bib pocket for the entire depth of each of the opposed walls of the bib pocket, the opposite ends of the strip tubes terminating closely adjacent to the upper edges of the bib pocket portion, the strip tubes of front wall 14 terminating slightly short of the free terminal edge of said front wall, and the strip tubes of the rear wall 19 preferably extending slightly beyond the upper edge of the bib pocket.

Within each of the elongated strip tubes 18 and extending the length thereof, there is mounted an elongated strip 20 of pliantly bendable inert material, preferably metal, which is inherently form-retaining when bent, such as strip-lead, strip-copper or tinier thin sheet metal, which are also rust-resistant, or other similar suitable compounded pliant non-spring strip metals available in the commercial market. In the formed bib the strip 20 is angularly bent upon itself centrally intermediate of its length, as at 21, the angular bend substantially conforming to the angle of the connected pocket walls at the bottom of the pocket, but the angle directly at said bend being in an arc rather than at an acute angle, in order to avoid fatigue and crystallization of the metal strip from repeated bending, such bending providing in the metal strip a pair of angularly disposed legs 22, 23 the planes of which substantially overlie relatively, the rear leg 23 preferably being slightly longer than the front leg 22, whereby the front leg 22 terminates adjacent to the upper free edge of the bib pocket, and the rear leg 23 extends into the breast portion of the bib slightly above the said pocket edge. The bendable strips 20 are slightly narrower than the strip tubes 18 so that they slide readily thereinto when the bib sheet and strips 20 are in aligned flat planar form, one end of the strip tubes being maintained open for sliding the strips 20 thereinto, and the end of the strip tube being thereupon sealed, whereupon the bib sheet and strips 20 may be suitably bent upon themselves, as will be further described, the strip tubes and the strips 20 being thus positioned vertically transversely relative to the horizontal longitudinally elongated pocket.

In operation, the bib is employed in the usual manner of pocketed bibs of over-all flexible material, but due to the pliability and form-retaining qualities of the strips 20, the pocket may be selectively opened or closed by respectively relatively spreading or closing the free terminal end portions of the legs 22, 23 at the angular connection 21 thereof, which, due to the form-retaining quality of the strips, will maintain such selective position until readjusted to an alternate selective position.

It is to be observed that the strips 20 are shielded by bib material to provide against possibility of injury to a child wearing the bib, and further, that the bib may

be packed flatly substantially in a plane by closing the pocket and the legs 22, 23 of the pliant strips 20 as shown in broken lines of FIG. 2; or, when the legs are thus closed, and due to the relative spacing of the said strips, and the over-all flexibility of the breast sheet and pocket, the bib may be folded or crumpled between and around the strip legs, either vertically, horizontally or in any other desired direction for flat or crushed or folded packing in a receptacle or storage space such as a handbag, a suit pocket, glove compartment of an automobile, or the like.

In FIGS. 5 and 6 a modified form of bib structure is shown in which the breast portion 11 and the operational parts are substantially similar to those hereinabove described, the modification being in providing a bib pocket 30 the opposing walls of which are relatively overlying sheets of the flexible moisture-impervious plastic sheet material, as indicated 31, 32, the inner sheet 31 being a continuation of the breast portion 11 retroverted upon itself at 33. The outer sheet 32 of the bib pocket may be a separate sheet overlying the bib pocket portion of the inner sheet 31, said inner and outer sheets of the pocket being suitably sealed relatively at the upper longitudinal edges of the front and rear walls of the pocket portion, and at the opposite ends of the pocket, as at 34 and 35, the entire body of the bib other than the pliant strips being freely flexible for folding or crumpling, as previously described.

The strip tubes 36 are provided in the walls of the bib pocket by stitching or plastic welding together of the overlying sheets of the pocket material at edges of the strip tubes as at 37, leaving one end of the strip tubes open for inserting the bendable strips 20 therein, and thereupon sealing the said tube end opening, after inserting the bendable strips 20 therein.

As best illustrated in FIGS. 2 and 5 the longitudinal length of the upper portion of the front wall of the pocket coupled with the secure closing of the opposite ends of the pocket, and more particularly, the adjacent spaced relation of the respective pliant strips to the opposite end closures of the pockets, limits the pliant relative spreading movement of the legs 22, 23 away from each other, to an acute-angle relationship to a normal flat plane of the breast sheet and the integral rearward wall of the pocket, which, in general is substantially the normal position of the breast sheet when the bib is positioned on a wearer. However, since the strips 20 are pliant it is to be understood that the legs of the strips 20 may be spread to a greater extent by also sufficiently deforming the breast sheet portion and the flexible rear wall of the pocket when the bib is not being worn by a wearer, such facility for a greater width of opening of the pocket being very advantageous for cleaning and washing the inside of the pocket, when the bib is not being worn by a wearer.

It is to be observed that in forming the bib it is preferred that the strips 20 shall be inserted into the strip tubes in aligned form while the bib sheet is in flat planar form, the strip tubes and preferably also the longitudinal welds 34 of the modification of FIGS. 5 and 6, having been formed therein and one end of the strip tubes being left open for the purpose of inserting the strips 20 therein. The bib pocket portion and the strips 20 are then bent upon themselves into the overlying relation as described, whereupon the opposite ends of the bib pocket and the remaining open end of the strip tubes may be sealed. To provide the arcuate bend 21 in the strip 20, the bending of the strip may be around a tubular rod of appropriately small diameter.

It is to be further understood that while dielectric plastic welding has been described in the specification, other means of sealing or connecting of the parts may be substituted therefor, such as stitching.

Having described the invention, what is claimed as new and patentable is:

1. A bib of flexible sheet material having an upper breast sheet portion, a horizontally transverse elongated bib pocket at the lower portion of the breast sheet, said pocket having a front wall of flexible sheet material overlying a lower portion of one face of the breast sheet providing relatively overlying opposed flexible front and rear walls connected at the bottom of the pocket, said pocket having its opposite ends and a lower longitudinal edge securely closed and being open at its opposite upper longitudinal edge portion, the upper free edge of said front wall being freely flexible, and angularly bent strips of pliant inert material spaced from the opposite ends of the pocket and spaced relative to each other, each of said strips having legs which respectively engage the said front and rear walls of the bib pocket laterally transversely of the length of the elongated pocket and extending from the bottom of the bib pocket towards the upper edge portion thereof and terminating adjacent to the upper open edge portion of the pocket, said pliant strips of bendable material being inherently form-retaining when bent, whereby said pocket opening may be selectively held at open and closed positions responsive to the selective bending of said strips, said breast sheet and pocket portions being freely flexible throughout the area thereof other than the area occupied by said pliant strips, whereby said freely flexible portion may be manipulated to selective shapes and forms around said pliant strips.
2. A bib of the character described as set forth in claim 1, the said bib pocket being of weldable plastic material and having relatively spaced strip tubes of flexible weldable plastic material plastically welded to its relatively opposed front and rear walls, said strip tubes extending from the bottom of the pocket to substantially the upper portion of the pocket, and said pliant strips being mounted in said strip tubes.
3. A bib of flexible sheet material as set forth in claim 1, the walls of the pocket being connected angularly at the bottom of the pocket, said pliant strips being angularly bent substantially conformable to said angle of the overlying flexible walls of the pocket, and said respective angled portions of the pocket and pliant strips being engaged relatively at the bottom of the pocket, the length of the upper portion of the front wall of the pocket and the closing of the opposite ends of the pocket and the spacing of the respective pliant strip members from adjacent ends of the pocket being related and arranged whereby the movement of the legs of the respective pliant strips away from each other is limited to an acute angular position relative to a normal flat plane of the breast sheet.
4. A device of the character described as set forth in claim 3, and in which each of the pliant strips of bendable material is bent arcuately upon itself in a relatively small arc at said angle and has legs extending upwardly from the bottom of the bib pocket in relatively angularly disposed overlying relation, said relatively small arc having a radius limited to preventing an acute angle immediately at the point of bending of said strips
